UNITED STATES PATENT OFFICE.

JEAN CHARLES WORTH, OF PARIS, FRANCE, ASSIGNOR TO DAVID CRYSTAL, INC., OF NEW YORK, N. Y., A CORPORATION OF NEW YORK.

DESIGN FOR A DRESS.

Application filed April 8, 1927. Serial No. 21,511. Term of patent 3½ years.

To all whom it may concern:

Be it known that I, JEAN CHARLES WORTH, a citizen of France, and a resident of Paris, France, have invented a new, original, and ornamental Design for Dress, of which the following is a specification, reference being had to the accompanying drawing, forming part thereof.

I claim:

The ornamental design for a dress, substantially as shown.

JEAN CHARLES WORTH.
